(57) **CLAIM**

The ornamental design for a push up board, as shown and described.

DESCRIPTION

FIG. 1 is a front perspective view of the push up board, shown in an open configuration;

FIG. 2 is a rear perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof;

FIG. 9 is a front perspective view thereof, shown in a folded configuration; and,

FIG. 10 is a front perspective view thereof, shown in an open, alternate configuration.

The dashed broken lines in the figures are for the purposes of illustrating portions of the push up board that form no part of the claimed design.

In the rear views, the unshaded areas shown between broken lines and between a solid line edge and a broken line form no part of the claimed design.
